UNITED STATES PATENT OFFICE.

JOSEPH A. OSBORN, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

ELECTRIC SWITCH.

1,109,594.

Specification of Letters Patent.

Patented Sept. 1, 1914.

Application filed June 1, 1911. Serial No. 630,705.

To all whom it may concern:

Be it known that I, JOSEPH A. OSBORN, residing at St. Louis, Missouri, and being a citizen of the United States, have invented 5 certain new and useful Improvements in Electric Switches, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact 10 details of construction shown and described, 15 as it is obvious that various modifications thereof will occur to persons skilled in the art.

In said drawings: Figure 1 is a side elevational view of a switch constructed in accordance with the invention, the protecting hood therefor being illustrated in transverse section. Fig. 2 is a view similar to Fig. 1, but showing the electrodes-connecting member moved into connecting position, parts of 20 the protecting hood being broken away for the saving of space. Fig. 3 is an end elevational view of the switch illustrating the supporting medium therefor in transverse section and Fig. 4 is a top plan view of the 25 switch, the protecting hood being illustrated in section.

The invention relates to an electric switch adapted particularly to be used in connection with the operation of hand-operated 30 electric welding tools, such as are illustrated in my prior patents, 1,042,467 and 1,042,468, dated Oct. 29, 1912.

The object of the invention is to provide a switch of simple, substantial and properly 35 insulated construction so formed as to be readily carried upon the handle of the welding tool in such a position as to be subject to convenient operation by the hand of the operator at any time during his use of the tool. 40 A further object is to provide for the ready removal of the electrodes when worn or damaged.

With these and other objects in view the invention comprises a base plate 1, integral 45 with which are formed two pairs of depending legs, as 2 and 3. The pairs are disposed relatively at opposite ends of the base plate 1, and the two comprising each pair are spaced apart so as to straddle the handle of

the tool to which the device is applied and 55 the lower ends of each pair are connected together by suitable bolts 4, provided with nuts 5, adapted for squeezing the legs against opposite sides of the tool handle for retaining 60 the switch in a fixed position.

A wall 6, is formed integral with and up-stands from the base plate 1, at the forward end thereof, that is, the end of said base plate, adjacent the hand-grip of the tool, from whence the pair of legs 2 depend. The 65 wall 6, extends transversely of the base plate and projects beyond the outer longitudinal edges thereof, and said extended portions are formed at their ends each with a vertically disposed groove 7, which grooves combine 70 to form a pocket into which is fitted an insulating member 8. The member 8, extends from one of the grooves 7, to the other and is adapted to be readily lifted from the pocket formed by said grooves when occa- 75 sion requires.

The entire upper surface of the base plate is covered by an insulating plate 9, and the lower edge of the insulating member 8, is adapted to rest preferably upon the upper 80 surface of the insulating plate 9. Fixed to the rear face of the insulating member 8, is a pair of electrodes as 10 and 11, spaced apart and thoroughly insulated from each other by a section of insulation 12, formed integral 85 with, or fixed to the face of the insulating member 8.

Each of the electrodes 10 and 11 comprise a rectangular piece of conductive material at the lower end of which is formed a laterally projecting ear 13 and 14, respectively, adapted for attaching conductors for supplying the electric current to the switch.

The rear faces of the electrodes 10 and 11, are disposed in the same vertical plane, and 90 the rear face of the insulating section 12 is projected beyond the adjacent faces of the electrodes 10 and 11, so as to effectually prevent unintentional passage of current from one electrode into the other.

The electrodes-connecting member as 15, is slidably mounted upon the upper surface of the insulating plate 9 rearward of the electrodes 10 and 11, and is fixed to an insulating plate 16, which is in turn pivotally 105 connected to a pair of links 17-17, which links extend forwardly through elongated apertures 6^a-6^a formed in the wall 6, and

- through similar apertures 8—8* formed in the insulating member 8. At their forward ends the links 17 are pivotally connected to the upper end of an operating lever 18 by 5 a transversely extending shaft 18*. The lever 18, is pivotally connected at its lower end, as at 19, to the bolt at the lower end of the pair of legs 2, and at its upper end is formed with a thumb-grip 20, which in use, 10 is adapted to project into proximity with the hand-grip of the handle of the tool so that it may be conveniently manipulated for drawing the electrodes-connecting member into contact with the electrodes.
- 15 The connection between the links 17, and the insulating plate 16 may be of any approved form but preferably comprises a knife-bar 21 fixed to the rear ends of the links 17. The edge of the knife-bar is uniform and continuous from one of the links 17 to the other and bears evenly against the rear surface of the insulating plate 16.
- 20 The links extend through apertures 22—22 in the insulating plate 16, and through apertures formed in opposite ends of the knife-bar, and a suitable adjusting nut as 23, is fixed to the end of each of the links for retaining the knife-bar.
- 25 Upon the forward side of the insulating plate 16, each of the links is fitted with an adjustable nut 24, formed with a convex surface adapted to engage a correspondingly concaved portion of the face of said insulating member. The apertures 22 are sufficiently large to permit of a rocking motion of the links without affecting the vertical position of the member 16.
- 30 A protecting cover 25, rectangular in shape is fixed to the under-side of the base plate 1, by suitable nuts as at 26, and extends upwardly upon the opposite sides of the switch and across the top thereof so as to avoid all danger to the operator.
- 35 A tension spring 27, engages the operating lever 18, and is so arranged as to maintain the electrodes-connecting member normally spaced away from the electrodes.
- 40 A suitable fiber washer 28, is arranged about the forward end of each of the links 17 so as to cushion the return of the operating lever.
- 45 The conductors as 28 and 29 lead to the ears 13 and 14, respectively preferably through suitable apertures as 30, formed in the under-side of the protecting cover 25.
- 50 From the foregoing it will be understood that when the thumb-grip 20, is depressed against the tension of the spring 27 the electrodes-connecting member 15 will be moved into contact with the electrodes 10 and 11, whereupon the electric current will be free to pass from the conductor 28 into the electrode 11, and through the electrodes-connecting member 15, into the electrode 10, and thence into the return conductor 29.

Having thus described my invention, what I claim as new and desire to secure by Letters-Patent is—

1. In an electric switch, a base plate, an insulating plate on said base plate, a carrying handle, a pair of electrodes supported upon said insulating plate, an insulating member between therein, an insulating current jump-guard extension on the latter projecting beyond said electrode, a current-conducting member movably supported on said insulating plate, spaced contact extensions thereon, said insulating guard being adapted to project between said contacts, a pivotally mounted lever adjacent said handle, a link paralleling said base, and connecting said lever with said movable member, whereby the contact extensions of said member may be drawn into contact with said electrodes. 70
2. In an electric switch, a base plate, an insulating plate thereon, a pair of electrodes supported upon said insulating plate, an insulating member between said electrodes extending therebeyond to form a current jump-guard, a slidably mounted member adapted for electrically connecting said electrodes, a pair of links embracing said electrodes and parallel with said base connected with said member, a depending lug formed upon said base plate, a lever pivotally supported upon said lug and being connected with said links, and a thumb-grip formed upon said lever for operating said lever and moving said electrodes-connecting member. 75
3. In an electric switch, a base plate, a pair of electrodes supported upon said base plate, a pocket adapted for removably retaining said electrodes, an insulating member between said pocket and said electrodes, means for electrically connecting said electrodes, and means extending through said insulating member adapted for operating said last mentioned means. 80
4. In an electric switch, a base plate, a pair of electrodes supported upon said base plate, an upstanding wall formed upon said base plate comprising a pocket adapted for removably retaining said electrodes, an insulating member between said wall and said electrodes and being fixed to said electrodes and engaging said pocket, means for electrically connecting said electrodes, and means extending through said insulating member and through said wall adapted for 90
- 100 operating said last mentioned means.
5. In an electric switch, a base plate, a pair of electrodes supported upon said base plate, a member adapted for electrically connecting said electrodes, said member being movably supported upon said base plate, an insulating member fixed to said electrodes-connecting member, a knife-bar engaging said insulating member, and means fixed to said knife-bar extending through 110
- 115
- 120
- 125
- 130

said insulating member adapted for moving said electrodes-connecting member into contact with said electrodes.

6. In an electric switch, a base plate, a pair of electrodes supported upon said base plate, an upstanding wall formed upon said base plate comprising a pocket adapted for removably retaining said electrodes, an insulating member between said wall and said electrodes and being fixed to said electrodes and engaging said pocket, a member adapted for electrically connecting said electrodes, an insulating member fixed to said electrodes-connecting member, a knife-bar engag-
15 gaging said insulating member, and means fixed to said knife-bar extending through said insulating member and through said wall adapted for moving said electrodes-connecting member into contact with said electrodes.

7. In an electric switch, a base plate, an insulating plate on said base plate, an insulating front plate, a wall projecting from said base plate, extensions therefrom embrac-
25 ing and retaining said front plate, a pair of electrodes disposed at the back of said front plate and supported on said insulating plate, an insulating member forming a part of said front plate separating said electrodes and
30 projecting therebeyond to form a current jump-guard, a rear insulating plate movable on the insulating plate on the base plate relative to said electrodes, and an electrode connecting member disposed at the front face
35 of said rear plate and movable therewith to contact electrically with said electrodes and to embrace said guard.

8. In an electric switch, an insulating base

plate, an insulating front plate, a pair of electrodes disposed at the back of said front plate and mounted upon said base plate, an insulating member projecting rearwardly from said front plate beyond and separating said electrodes, a rear insulating plate movable on said base plate relative to said electrodes, an electrode connecting member disposed at the front face of said rear plate and movable therewith to contact electrically with said electrodes, said electrode having a recess adapted to contain part of said insulating member, constituting means for centering said connecting member on said electrodes.

9. In a welding device, a handle, a base plate, members depending therefrom secured to said handle, a wall upstanding from said base plate having spaced apertures therein, a pair of stationary electrodes mounted on said base plate, secured to said wall and insulated from both and from each other, a movable electrode connecting member also mounted and insulated from said base plate, a manually controlled lever carried by said handle, and spaced apart links on opposite sides thereof passing through said apertures and each forming a connection between said lever and movable member whereby the actuation of said lever will bring said movable member into contact with both of said electrodes.

It witness whereof I have hereunto set my hand in the presence of two witnesses.

JOSEPH A. OSBORN.
